UNITED STATES PATENT OFFICE.

ALVIS F. CROOM, OF DALLAS, TEXAS.

DESIGN FOR A RIDING-SADDLE.

SPECIFICATION forming part of Design No. 34,766, dated July 9, 1901.

Application filed April 26, 1901. Serial No. 57,635. Term of patent 7 years.

To all whom it may concern:

Be it known that I, ALVIS F. CROOM, a citizen of the United States, residing at Dallas, in the county of Dallas and State of Texas, have invented and produced a new and original Design for Riding-Saddles, of which the following is a specification.

My invention relates to a new and original design for riding-saddles, and is illustrated in the accompanying drawing, in which the figure is a side elevation.

In the drawing I have shown but one side of my new design for a saddle, the other side being precisely similar in all respects.

As shown in the drawing, the leading or material feature of my design consists of a riding-saddle having a horn or pommel rising from its front end and provided with a forwardly-pointing beak and a neck protruding from a cover, having a line of lacing at the base of the horn or pommel, the saddle having a rear cantle rising at the rear thereof and rearwardly inclined, and provided also with front and rear housings formed with straight lower edges and in substantial horizontal alinement and ornamental middle jockeys between the front and rear housings having rounded lower edges projecting below the lower line of the front and rear housings.

In the said drawing the reference-numeral 1 indicates the horn or pommel rising from the front end of the saddle and provided with a forwardly-pointing beak 1^a and the neck 1^b, protruding from a cover 1^c, which is provided with a line of lacing 1^d at the base of the horn or pommel.

The numeral 2 indicates the rear cantle ris-

ing at the rear of the saddle and rearwardly inclined, as shown.

The numeral 3 indicates the seat, 4 the front housing, and 5 the rear housing, which are formed with straight lower edges 6 7 in substantial horizontal alinement.

The middle jockeys, only one of which is shown, are indicated by the numeral 8. They are between the front and rear housings and have rounded lower edges 9, which project below the lower line of the front and rear housings, and they are provided with ornaments 9^a. Connected to the front housing at a point 10 is a loop 11, and to the rear housing and rear part of the jockey at the point 12 13 is a loop 14.

15 indicates pendent straps hanging from the loops 11 and 14.

16 indicates ornamental leg-pads depending in line with the middle jockeys, and 17 indicates stirrup-straps.

18 represents rosettes, and 19 streamers.

My design presents a riding-saddle of novel, pleasing, and distinguished appearances.

Having thus described my invention, what I claim, and desire to secure by Letters Patent, is—

The design for a riding-saddle substantially as herein shown and described.

In testimony whereof I have hereunto set my hand in presence of two subscribing witnesses.

ALVIS F. CROOM.
